UNITED STATES PATENT OFFICE.

AUGUST CORTS, OF WYNCOTE, PENNSYLVANIA, ASSIGNOR TO WILLIAM WHARTON, JR., & COMPANY, INCORPORATED, OF PHILADELPHIA, PENNSYLVANIA, A CORPORATION OF PENNSYLVANIA.

GUARD-RAIL FOR RAILROAD-TRACKS.

SPECIFICATION forming part of Letters Patent No. 759,677, dated May 10, 1904.

Application filed March 14, 1904. Serial No. 197,962. (No model.)

To all whom it may concern:

Be it known that I, AUGUST CORTS, a citizen of the United States, residing at Wyncote, Pennsylvania, have invented certain Improvements in Guard-Rails for Railroad-Tracks, of which the following is a specification.

My invention relates to certain improvements in guard-rails and spacing devices for separating the guard-rail from the main rail of a railway-track.

The object of my invention is to simplify track structures of this type by making one of the spacing-blocks integral with the guard-rail or with the facing portion of the guard-rail, as fully described hereinafter, reference being had to the accompanying drawings, in which—

Figure 1 is a plan view of a main rail and a guard-rail, illustrating my invention. Fig. 2 is an enlarged transverse sectional view on the line 2 2, Fig. 1. Fig. 3 is a perspective view of the guard-rail, the facing portion, and the wedges illustrated in Fig. 1, the parts being detached. Fig. 4 is a perspective view showing a modification of the guard-rail illustrated in Fig. 1. Fig. 5 is an enlarged sectional view similar to Fig. 2, but illustrating the modification shown in Fig. 4.

A is the main rail of a railroad-track. B is the guard-rail, secured to the main rail in the present instance by clamps C and wedges c.

It has been a common practice to place two wedge-shaped blocks between the guard-rail and the main rail with their inclined sides bearing against each other, so that as the face of the guard-rail wears away it can be moved toward the main rail by properly adjusting the spacing-blocks, thus keeping the space between the rails of a standard width. Heretofore both wedges have been loose and separate from the rails, while different means have been provided for holding them in position; but by my invention I make one of the wedge blocks integral with the guard-rail and only the other block loose and adjustable.

Referring to Figs. 1, 2, and 3, I have shown

a guard-rail B made in two parts—a facing portion and a body portion, the facing portion D being mounted in a recess in the body portion of the guard-rail, the rail in this case being a section of an ordinary railroad-rail bent outward at each end. As illustrated in Fig. 3, the facing portion and the body portion are each provided with holes for the passage of rivets, bolts, or other securing devices for securely attaching the facing portion to the body portion of the rail.

The facing D is preferably of hard metal, such as manganese-steel, and cast integral therewith are wedge-shaped blocks d d, two in the present instance, having ribbed faces which interlock with the ribbed faces on the detachable wedge blocks F F. The backs of the detachable wedge blocks F fit between the head and the base-flange of the main rail, as illustrated in Fig. 2.

In some instances I may make the entire guard-rail of a casting of hard metal, such as manganese-steel, and this form of rail is clearly illustrated in Figs. 4 and 5.

B' is a cast rail of this kind having the wedge-shaped spacing-blocks d' d' formed integral therewith, these spacing-blocks having ribbed faces which interlock with the ribbed faces of the detachable wedge spacing-blocks F F.

I claim as my invention—

1. A guard-rail for railroad-tracks having a wedge-shaped spacing-block formed integral therewith, substantially as described.

2. A guard-rail for railroad-tracks having a wedge-shaped spacing-block formed integral therewith, said wedge-block having a ribbed face, substantially as described.

3. The combination in a guard-rail, of a facing portion having a wedge-shaped spacing-block formed integral therewith, a body portion, and means for securing the two parts together, substantially as described.

4. The combination in a guard-rail, of a hard-metal facing portion having a wedge-shaped spacing-block formed integral there-

with, a body portion recessed to receive the facing, and means for securing the two parts together, substantially as described.

5. The combination of a main rail, a guard-rail, a permanent wedge block formed integral with the guard-rail, and a detachable wedge block placed between the permanent wedge block and the main rail, and means for securing the guard-rail to the main rail, substantially as described.

6. As a new article of manufacture, a guard-

rail for railway-tracks having a spacing-block formed integral therewith, substantially as described.

In testimony whereof I have signed my name ¹⁵ to this specification in the presence of two subscribing witnesses.

AUGUST CORTS.
